EVAPORATIVE COOLER

Gordon D. Petrie, Phoenix, Ariz., assignor to Wright Mfg. Company, Phoenix, Ariz., a corporation of Arizona

Application August 1, 1957, Serial No. 47,195

Term of patent 14 years

(Cl. D62—4)

Fig. 1

Fig. 2

Fig. 3

Fig. 4

Fig. 1 is a front perspective view of an evaporative cooler showing my new design.

Fig. 2 is a plan view of the evaporative cooler shown in Fig. 1.

Fig. 3 is a front elevation of the evaporative cooler shown in Figs. 1 and 2, the rear elevation being identical.

Fig. 4 is a left hand side elevation of the evaporative cooler shown in Figs. 1, 2 and 3, the right hand side elevation being identical.

The areas beneath the grilled areas in Figs. 1 and 3 are louvered.

I claim:

The ornamental design for an evaporative cooler, as shown and described.
